UNITED STATES PATENT OFFICE.

IRA DICK, OF MUNCIE, INDIANA.

MEANS FOR TIGHTENING BOLTING-CLOTHS.

SPECIFICATION forming part of Letters Patent No. 244,383, dated July 19, 1881.

Application filed March 28, 1881. (No model.)

To all whom it may concern:

Be it known that I, IRA DICK, a citizen of the United States, residing at Muncie, in the county of Delaware and State of Indiana, have 5 invented a new and useful Improvement in Means for Tightening Bolting-Cloths, &c., of which the following is a specification.

My invention relates to improvements in that class of devices for tightening bolting-cloths 10 in which the cloth is tacked to a strip of wood, which is operated in combination with the shaker-frame, and in which thumb-screws are used for tightening the cloth; and the objects of my invention are, first, to construct a simple device for stretching the cloth each way, (in length and breadth;) second, to arrange a shaker-frame so that the tightening device can be operated when the machine is in motion, and especially, third, to facilitate the tightening 15 of bolting-cloths on middlings-purifiers. I attain these objects by the mechanism illustrated in the accompanying drawings, in which—

Figure 1 is a top view of the shaker-frame, 25 showing its construction. Fig. 2 is an end view of one of the sides (or ends) of the shaker-frame, showing the two thumb-screws (or the adjusting and clamping bolts) and all of the co-operating parts. Fig. 3 is a perspective view 30 of one of the sides of the frame, showing the slots in the cleat in which the clamp-screws work. Fig. 4 is an end view of one of the sides, showing another form of supporting the cloth-bar. Fig. 5 is a perspective view of the cleat-bar corresponding to the form in Fig. 4.

Similar letters refer to similar parts throughout the several views.

The sides and ends of the frame are marked *a*, *b*, and *e*, and are braced across the center 40 by bars *t*. *a* are the rails of the frame, through the lower edge of which the adjusting-screws

pass, and at or near the middle of the inside of the said rails the cleat-bar *b* is secured by screws, as shown in Fig. 3. The said cleats have slots cut in them, as shown in Figs. 3 and 45 5. Through each of these slots a clamp-screw, *c*, passes. When the clamp-screw *c* is loose the cloth-bar *e* can be easily moved by the adjusting-screw *f*. To the under side of the bar *e* the cloth *i* is tacked, or it may be secured to one 50 side and bottom of the bar *e*, as shown at Figs. 2 and 4. The adjusting-bolt *f* passes through the lower portion of the bar *a* and through the cloth-bar *e* horizontally. The clamp-screw *c* passes through the cleat *b* and cloth-bar *e* perpendicularly. The clamp-screw *c* is for the purpose 55 of keeping the cloth-bar *e* and the cleat clamped tight together. To operate the device it is only necessary to loosen the screw *c* and then loosen or tighten the cloth, as desired, 60 by the adjusting-screw *f*.

Having thus described my invention, what I claim as new, and desire to secure by Letters Patent, is—

1. In a shaker-frame, the combination, with 65 the cloth-bar and a supporting-bolt, of the clamp-bar having grooves or slots, for the purpose set forth.

2. In a shaker-frame, the combination of the clamp-bar and the cloth-bar having a clamp-bolt passing through it perpendicularly and an adjusting-bolt passing through it horizontally into the side rails of the shaker-frame, for the 70 purpose set forth.

3. The combination of the bar *a*, cleat or 75 clamp-bar *b*, clamp-screws *c* and *n*, and the adjusting-screws *f*, substantially as and for the purpose set forth.

IRA DICK.
